G. H. UHLER

DISPLAY RACK

Filed Jan. 5, 1923

UNITED STATES PATENT OFFICE.

GEORGE H. UHLER, OF MARION, OHIO.

DISPLAY RACK.

Application filed January 5, 1923. Serial No. 610,825.

This invention is a device for conveniently displaying rugs and similar heavy fabrics.

In displaying heavy fabrics, such as rugs and the like, for sale, it is customary to place them flat, one upon the other, upon a suitable platform, or else to suspend them from overhanging swinging supports. The first method has the advantage of displaying the 10 rugs in a minimum space and in a position in which the customer may inspect the whole rug, but it is open to the objection that the rugs must be lifted off or folded back, one at a time, in order that a customer may view 15 them all. The second method has the advantage of permitting each rug to be brought to view with little labor, but is open to the objection that much more expensive apparatus is necessary than in the first method, 20 overhead space is required, and the entire rug may not be closely inspected unless taken down and placed upon the floor of the salesroom.

One of the objects of the invention is to 25 overcome the foregoing difficulties, by providing a display device so constructed that the rugs may be piled one upon the other, close to the floor, and having means whereby any number of superposed rugs may be 30 conveniently folded back to permit of the inspection of any selected rug in the pile. A further object is to provide a display rack having means so constructed that the weight 35 of the rugs which have been folded back, will be utilized to retain them in their new position relative to the rest of the rugs remaining in the original pile. A further object is to provide convenient storage space 40 for rugs which have been removed from the pile and rolled, preparatory to delivery to a purchaser.

The invention will be hereinafter fully set forth and particularly pointed out in the 45 claims.

In the accompanying drawings:—

Figure 1 is a perspective view illustrating a display rack constructed in accordance with the invention. Figure 2 is a detail view illustrating the crank shaft bearing and 50 rack guide.

Referring to the drawing, 10 designates a base constructed of any suitable material, on which is mounted the main support 11. Said main support is preferably of ap-

proximate inverted V-shape, constructed 55 with sloping top walls converging to a line located above the middle of the base, and it cooperates with said base to provide a substantial storage space 12. As shown, the main support consists of a suitable frame, 60 provided with a covering forming the sloping top walls.

Movably mounted with relation to the main frame is a supplemental frame, consisting of end bars 13, pivoted at their lower 65 ends to the lower portion of one of the sloping top walls of the main frame. The pivotal connections may be made in any desired manner, for instance, by means of hinges 14. The upper ends of the bars 13 are connected by a cross piece 15.

Pivotedly connected at one end to the respective end bars 13, are toothed rack bars 16, having their free ends mounted in and guided by guide members 17, secured to the 75 main support 11. An operating shaft 18, extending under one of the sloping top walls of the main support 11, within the space 12, is mounted in suitable bearings 19, secured to said main support. Said shaft is 80 provided with toothed pinions 20, meshing with the teeth of the rack bars 16. A crank handle 21 is provided for rotating said shaft.

In practice, the rugs, illustrated in dotted lines, are piled one upon the other, upon the 85 main support, as shown in Figure 1, the supplemental support normally lying against the topmost rug. In displaying the rugs to a customer, the salesman folds them, one at a time, over the supplemental support in 90 superposed relation, until a rug is reached which the customer desires to inspect more closely. The salesman then rotates the shaft 18, by means of the crank 21, in a direction to cause the racks 16 to move the supplemental support, with the rugs folded thereover, away from the main support to the 95 position illustrated in Figure 1, movement of the racks being limited by stops 17a. In

this position the weight of the rugs on the 100 supplemental support tends to hold the latter away from the main support, and the entire surface of the topmost rug upon the latter is exposed to view. If, after the customer inspects the rug, a sale is made, the desired rug is removed, and the shaft 18 is 105 operated to bring the supplemental support back to its normal position against the main

support. The folded rugs are then turned back and replaced upon said main support, the selected rug having been rolled and placed in the space 12. If a sale is not made 5 and the customer desires to examine the rest of the rugs, the supplemental frame, carrying the folded rugs, is moved back to its normal position against the main support, so that the salesman may fold other rugs there- 10 over, in the manner already described.

The advantages of the invention will be readily apparent. It will be particularly observed that the rugs are supported close to the floor in a convenient position for close 15 inspection, and that any number of super- posed rugs may be easily folded back to permit of a close inspection of any selected rug in the pile. The device is so arranged that the weight of the folded rugs is utilized to 20 retain the supplemental support in its ad- justed position. After the rug has been removed from the main support it may be rolled and placed within the storage space 12, until a convenient time of delivery.

Having thus explained the nature of the 25 invention, and described an operative manner of constructing and using the same, al- though without attempting to set forth all 30 of the forms in which it may be made, or all of the forms of its use, what is claimed is:—

1. A display rack comprising a main sup- 35 port upon which a plurality of rugs may be flatly spread out in a pile, a supplemental support movably connected with the main support contiguous to the bottom thereof and adapted to normally rest by gravity upon the topmost rug of the pile in such a position that any number of said rugs from the top down may be folded backwardly over 40 it, and means connected with the supple- mental support for moving it with respect to the main support so as to remove the folded over rugs to expose the topmost one of the rugs remaining on the main support.

2. A display rack comprising a main sup- 45 port constructed with downwardly and out- wardly diverging top walls upon which a plurality of rugs may be flatly spread out in a pile, a supplemental support movably 50 connected with one of said top walls con- tinuous to the bottom thereof and adapted to normally rest by gravity upon the top- most rug of the pile in such a position that any number of said rugs from the top down 55 may be folded backwardly over it, and means connected with the supplemental sup- port for moving it with respect to the main support so as to remove the folded over rugs and wholly expose the topmost one of the 60 rugs remaining on the main support.

3. A display rack comprising a main sup- 65 port upon which a plurality of rugs may be flatly spread out in a pile, said support being provided with a storage space, a supple- 70 mental support movably connected with the main

support contiguous to the bottom thereof and normally resting by gravity on the top- most rug of the pile in such a position that any number of said rugs from the top down may be folded backwardly over it, and means 75 connected with the supplemental support for moving it with respect to the main support so as to remove the folded over rugs and wholly expose the topmost one of the rugs remaining on the main support. 75

4. A display rack comprising a main sup- port upon which a plurality of rugs may be flatly spread out in a pile, a supplemental support movably connected with the main support contiguous to the bottom thereof and adapted to normally rest by gravity upon the topmost rug of the pile in such a position that any number of said rugs from the top down may be folded backwardly over it, actuating arms connected with said supplemental support, and means for oper- 80 ating said actuating arms so as to move the supplemental support with respect to the main support whereby the folded over rugs are removed and the topmost one of the rugs 85 remaining on the main support is wholly exposed.

5. A display rack comprising a main sup- port upon which a plurality of rugs may be flatly spread out in a pile, a supplemental support movably connected with the main support contiguous to the bottom thereof and adapted to normally rest by gravity upon the topmost rug of the pile in such a position that any number of said rugs from the top down may be folded backwardly over it, rack bars pivotally connected with the supplemental support, an operating shaft, and pinions on the operating shaft 90 95 100 105 110 115 120 125 130

engaging said rack bars.

6. A display rack comprising a main sup- port upon which a plurality of rugs may be flatly spread out in a pile, a supplemental support movably connected with the main support contiguous to the bottom thereof and adapted to normally rest by gravity upon the topmost rug of the pile in such a position that any number of said rugs from the top down may be folded backwardly over it, rack bars pivotally connected with the sup- 110 115 120 125 130

plemental support, an operating shaft, and pinions on the operating shaft engaging said rack bars, rack bar guide members secured to the main support, and bearings for the operating shaft made integral with the guide members.

7. A display rack comprising a main sup- port having downwardly and outwardly di- 125 130

from the top down may be folded backwardly over it, a shaft extending beneath said main support member and supported by the latter, and means connected with the supplemental support and actuated by said shaft for moving the supplemental support with respect to the main support so as to move

the folded over rugs and wholly expose the topmost one of the pile remaining on the main support.

In testimony whereof I have hereunto set my hand.

GEORGE H. UHLER.
